UNITED STATES PATENT OFFICE.

PAUL S. MENOUGH, OF WELLSVILLE, OHIO.

CASTING-MACHINE.

Specification of Letters Patent. Patented Nov. 30, 1915.

1,162,246.

Application filed April 26, 1913. Serial No. 763,752.

To all whom it may concern:

Be it known that I, PAUL S. MENOUGH, a citizen of the United States, residing at Wellsville, in the county of Columbiana and State of Ohio, have invented certain new and useful Improvements in Casting-Machines, of which the following is a specification, reference being had therein to the accompanying drawings.

10 This invention relates to machines for making small castings in permanent molds.

The machine as illustrated in the drawings is primarily intended for the production of iron castings, but I desire it to be understood that machines embodying my invention can be used for other metals, as, for instance, steel, bronze or aluminum. The machine is adapted for the making of small washers, but it will be understood that my 20 invention is not so limited and that the machine, with modifications, can be used for casting other small parts.

One of the objects of the invention is to provide a casting machine having an improved arrangement of mold sections, and controlling devices therefor.

Another object is to provide improved mold sections and improved devices for ejecting castings from the molds.

30 Another object is to provide improved means for moving and controlling the parts of the mold.

A further object is to provide an improved means for supplying molten metal to the 35 mold.

A still further object is to provide means whereby the various parts of the machine can be controlled and operated electrically.

Other objects will be apparent from the 40 following specification and claims.

Of the accompanying drawings, which illustrate the embodiment of my invention which I now deem preferable, Figure 1 is a plan view of a single machine with the 45 mold closed, the metal reservoir and associated parts being removed for the sake of clearness. It will be understood that in practice I prefer to use a battery of machines such as that shown in the drawings.

50 Fig. 2 is a plan view similar to Fig. 1 but showing the mold open. Fig. 3 is an end elevation of a single machine, together with part of an opposite or companion machine.

This view also shows the metal reservoir and 55 shows in section one of the valves for the molten metal. Fig. 4 is an end view of a

single machine. Fig. 5 is a view of the movable mold part, this view being taken along the line 5—5 of Fig. 2. Fig. 6 is a plan view, partly diagrammatic, of the controlling mechanism for the machine. Fig. 7 is an end view of a part of the controlling mechanism. Fig. 8 is a diagrammatic view of the entire apparatus showing the electrical connections.

60 Referring to the drawings, 1 represents a stationary mold section which is secured to and mounted upon the main base castings 2, 2. As shown in the drawings, this mold section 1 is simply a prismatic block of metal 70 with smooth parallel surfaces 3, 3, adapted to coöperate with mold sections 4, 4.

The molds which I have shown are adapted for the casting of washers and use is made of the plane surfaces 3, 3, of the block 1 75 which coöperate with the recesses or depressions 5, 5 in the blocks 4, 4 to form the outlines of the washers. When other devices are to be cast, the mold sections must obviously be correspondingly modified.

80 Each block or mold section 4 has secured to it frames or housings, 6, 6, in which are mounted wheels or rollers 7, 7. On the base castings 2, 2, are tracks 8, 8, which are adapted to engage with and support the wheels 7, 7. 85 The mold sections or blocks 4, 4, are supplementally guided and supported by means of pins 8^a which are rigidly mounted in the block 1 and which extend through suitable apertures in bosses 8^b, 8^b, on the blocks 4, 4.

90 9 is a cylinder for one of the mold sections 4. It is mounted on the outer parts of the base castings 2, 2. Slidably mounted within the cylinder is a piston 10 which has connected to it a rod 11.

95 At 12 there is a stuffing box for forming a tight joint around the rod.

The end of the piston rod 11 is pivotally connected at 13 to lugs or ears 14 on a flat vertical plate 15. Secured to this plate 15, 100 preferably by means of countersunk screws 15^a, are pins 16, 16, which extend through suitable apertures in the mold section 4 and into the recesses or depressions 5, 5, where they serve to form the eyes or holes in the 105 washers as they are cast. The ends of these pins 16, 16 are slightly tapered, as shown, in order to permit easy withdrawal.

110 The plate 15 is movable with respect to the block or mold section 4, but this movement is limited by the clips 17, 17 which extend over the ends of the plate. When the

piston and piston rod are moved outward in the manner to be described, the plate 15 and the pins 16, 16 are moved with them. In this way the ends of the pins are withdrawn 5 from the recesses and consequently from the washers which have been formed in the recesses 5, 5. However, as soon as the plate 15 contacts with the clips 17, 17, motion is transmitted to the mold section 4 and it is 10 moved outward with the plate to the position indicated in Fig. 2. On the return movement the plate is first moved into contact with the block and the pins are moved into the operative positions. Then the 15 block is moved with the plate and all of the parts are returned to the position shown in Fig. 1.

18 is a transverse strip or plate which is secured in place in any desired way, but 20 preferably by being caught under the nuts which hold the stuffing box 12 in place. This plate 18 carries at its ends small bearing castings 19, 19, which are apertured to receive pins 20, 20. These pins extend inward through suitable apertures in the mold section 4 and terminate at their inner ends in collars or enlargements 21, 21 which are normally seated in suitable recesses adjacent and joining the larger recesses 5, 5. 25 Each pin 20 carries an intermediate collar 22 and a spring 23 interposed between the collar 22 and the block 4 normally holds the pin in its outermost position. However, when the mold section 4 and associated 30 parts are retracted, as shown in Fig. 2, the collars 22 are engaged by the plate 18 and the pins are moved inward relative to the block or mold section 4 and serve to engage and eject the washers from the recesses of 35 the mold. As soon as the mold section returns to its normal position, as shown in Fig. 1, the springs 23 return the pins to their outermost positions. It will be understood that the number and position of the 40 pins 21 can be varied as found necessary.

For operating the piston 10 in the cylinder 9 use may be made of either compressed air or water under pressure. For present purposes I will refer to the motive fluid as air, but it will be understood that water or other fluid may be used if preferred.

24 and 25 represent ports communicating with the cylinder 9 at the inner and outer ends respectively.

55 26 and 27 are three-way valves. The valve 26 communicates with the supply pipe 28 and with the port 24 by means of the pipe 29. The valve 27 communicates with the supply pipe 28^a and with the port 25. The 60 discharge ducts for the valves are indicated at 26^a and 27^a. Each valve is so constructed that when in one position it will establish communication between the supply pipe and the corresponding port, and when in another 65 position, will establish communication be-

tween the port and the atmosphere through the corresponding discharge duct.

For operating the valves there are secured to them gear wheels 30 and 31. These gear wheels mesh with rack teeth formed on a bar 32 which is slideable horizontally through solenoids 33 and 34. When the solenoid 34 is energized, the rod 32 is moved to the position shown in Fig. 1 and the valve 27 is turned to admit pressure fluid to outer end of the cylinder. At the same time the valve 26 is moved to connect the inner end of the cylinder with the atmosphere. In this way the movable mold section 4 is forced against the stationary mold section 1. When the solenoid 33 is energized, the rod 32 is moved to the position shown in Fig. 2 and the valve 26 is turned to admit pressure fluid to the inner end of the cylinder 9. At the same time the valve is turned to connect the outer end of the cylinder with the atmosphere. In this way the piston is actuated to retract the movable mold section and to bring the parts into positions shown in Fig. 2.

For admitting metal to the mold recesses 5, 5 in the mold section 4, a gate opening 35 is provided which is preferably, though not necessarily, shaped in the manner shown in Fig. 5. This gate opening terminates at its upper end in a conical recess or sprue 36 formed partly in the mold section 4 and partly in the mold section 1.

37 is a reservoir for molten metal mounted above the molds. The reservoir extends over the entire battery of molds and serves 100 to supply all of them. It is preferably a suitably lined metal tank provided with pins 37^a, 37^a which are arranged to enter recesses 37^b in the stationary mold section 1 and to be in this way entirely supported.

38, 38 are short pipes or nipples positioned respectively immediately above the conical recess 36 and connected at their upper ends to the bottom wall of the reservoir 37. At the upper end of each pipe there is a conical 110 recess in the bottom wall of the reservoir.

39 is a valve mounted at the lower end of a vertical rod 40. This rod 40 is inclosed in a bushing 41 of refractory material such as porcelain. The porcelain sleeve or bushing 115 is held in place by means of nuts 42.

43 is a weight for holding the valve 39 normally in position. This weight can conveniently be formed by providing an iron shell and filling it with lead.

The rod 40 is, at its upper end, screwed into or otherwise secured to a bar 44 which is guided at its upper end in a bearing in a suitable framework 45.

46 is an approximately horizontal lever 125 which is pivoted between its ends at 47 to a bracket on the cross bar 47^a mounted on the reservoir. The inner end of the lever 46 is connected by means of a link 48 with the bar 44 connected to the rod 40. The other end 130

of the lever 46 is pivotally connected with a vertical rod 49, which, at its lower end, extends into a solenoid 50. A collar 51 on the rod 49 serves to limit its downward movement.

From the foregoing description it will be obvious that when the solenoid 50 is energized the rod 49 will be moved downward and the rod 40 will be moved upward to very quickly open the valve 39. As soon as the solenoid 50 is deenergized, the valve 39 will be quickly returned to its closed position by the weight 43.

It will be observed that the valve operating mechanism is mounted entirely on the reservoir and that the whole reservoir, together with the valves and operating mechanism, can be readily removed at will. However, it will be understood that temporary braces or stays may be used without departing from the spirit of this feature of my invention.

The several mold sections are provided with means whereby water or other fluid can be circulated through them to keep them cool. Preferably the mold sections are constructed by being cast around a system of pipes 52, such as indicated by dotted lines in Fig. 5. The end pipes of this system are connected by flexible tubing with a suitable source from which cold or cool water can be supplied. Fresh water can be used or, if preferred, the water can be run through a cooling system and used over again. When water is used in the operating cylinders it can, if desired, be passed from the cylinders through the cooling pipes.

Referring to Figs. 6 and 7, 53 represents the main shaft for the electrical controlling mechanism. This shaft can be driven in any desired way, but, for purposes of illustration, I have shown it driven from an electric motor 54 by means of gearing 55. The speed of rotation of the shaft 53 will depend upon the time required for the several operations of the casting machines, and can be adjusted in accordance with the conditions. Mounted upon this shaft 53 are disks of which one is provided for each machine. For the sake of simplicity, I have shown in the drawings but one such disk, this being represented by the reference character 56. Each disk is formed of insulating material such as fiber and has mounted upon its periphery contact plates 57, 58 and 59 which are spaced from each other both longitudinally and circumferentially. Mounted upon one side of each disk are three concentric metallic rings 60, 61 and 62. By means of suitable connections extending through the body of the disk, the contact 57 is connected with the ring 60, the contact 58 with the ring 61 and the contact 59 with the ring 62.

63 is a vertical plate for supporting a series of brushes. For each disk there are

horizontally pivoted to this plate at 64 three brushes 65, 66 and 67, arranged to contact, respectively, with the plates 57, 58 and 59. These brushes are properly insulated from the supporting plate. Extending horizontally from the plate 63 and insulated therefrom are brush arms 68, 69 and 70 arranged to contact, respectively, with the rings 60, 61 and 62.

The brushes 67 and 70 at one disk are connected through a suitable source of current with the solenoids 50 for operating the valves of companion machines. The brushes 65 and 68 are connected through a suitable source of current with the solenoid 33 for moving the valves to open the molds. The brushes 66 and 69 are connected through a suitable source of current with the solenoid 34 for moving the valves to close the molds.

Separate disks and separate brushes are provided for the several sets of machines in order that each may be controlled and stopped or started independently of the others. For providing this independent control manually controllable switches are interposed between the disks and the solenoids.

While I have shown and described the form of controlling mechanism, I now prefer it will be understood that as to the details of this part of my invention there may be wide variation.

For starting the operation of the apparatus it may be necessary to warm the valves 39 by means of a gas flame or otherwise. Assuming that this has been done and that the reservoir 37 is filled with molten metal, the operation will proceed as follows: As the contact strip 59 on the rotating disk 56 is engaged by the brush 67, the circuit is completed through the solenoids 50 and the rods 49 are jerked downward to quickly open the valves 39. This quick opening of the valves is of much importance as it prevents a thin stream of metal from first entering the valve apertures and the gates and becoming hardened. The length of the strip 59 is made such that the valves 39 will be held open just long enough to fill the molds. As soon as the strip 59 passes onward to break the circuit through the solenoids 50, the valves will be quickly shut by the weights 43. The contact strip or plate 57 is located at a position on the disk such that time is allowed for the castings to cool before it is engaged by its brush 65. As soon as it is engaged by the brush, the circuit is completed through the solenoids 33 and the parts are operated in the manner before described to bring the mold into the open position shown in Fig. 2 and to eject the castings. As soon as the molds are opened and the castings ejected, they are again closed by the contacting of the strip 58 with the brush 66 which completes the circuit through the solenoids 34, thus returning the parts to the position shown in Fig. 1.

4
A suitable receptacle can be provided beneath the machine for receiving the castings as they are ejected.

- 5 There are a number of advantages incident to the provision of two movable mold sections such as I provide, together with the two sets of operating devices therefor. By providing the two molds and the two motors, and by arranging them to act simultaneously 10 in opposition to each other, I avoid subjecting the central mold section to any severe strains. The movable sections contact with it on opposite sides at the same time and with equal pressure, and the result is that 15 the actions of the two movable sections balance each other so that the stationary section is not subjected to any forces tending to move it. By providing the two movable sections in combination with the central stationary section, I am enabled to make use of a single reservoir for the molten metal. The simultaneously opening valves 39, 39 admit the molten metal to both molds simultaneously.
- 20 25 What I claim is:
1. In a machine for making metal castings, the combination of a stationary support, a central mold section secured to the support, two movable mold sections at opposite sides of the central section and adapted to coöperate therewith to form two complete molds, means for supplying molten metal to the molds when the movable sections are in operative positions, two separate motors connected respectively to the two movable sections, and means for controlling the motors to cause them to simultaneously move the movable mold sections away from or toward each other out of or into operative positions.
  2. In a machine for making metal castings, the combination of a stationary support, a central mold section secured to the support, two movable mold sections at opposite sides of the central section and adapted to coöperate therewith to form two complete molds, means for supplying molten metal to the molds when the movable sections are in operative positions, two separate fluid pressure cylinders with pistons connected respectively to the two movable mold sections, and valve controlled pipes for conducting pressure fluid to the two cylinders to cause them to simultaneously move the movable mold sections away from or toward each other out of or into operative positions.
  3. In a machine for making metal castings, the combination of a stationary support, a central mold section secured to the support and provided with a plurality of spaced interior passages for a cooling fluid, two movable mold sections at opposite sides of the central section and each provided with a plurality of spaced interior passages for a cooling fluid, the movable sections being adapted to coöperate with the central

sections to form two complete molds, means for supplying molten metal to the molds when the movable sections are in operative positions, means for supplying cooling fluid to the passages in the three sections, and means for moving the said movable sections away from and toward the central section.

4. In a machine for making metal castings, the combination of a stationary support, a central mold section secured to the support, two movable mold sections at opposite sides of the central section and adapted to coöperate therewith to form two complete molds, the mold sections being provided with recesses adapted to form (when the movable sections are in operative positions) two separate gate openings, one for each mold, means for supplying molten metal simultaneously in two separate streams to the two gate openings, and means for moving the said movable sections away from and toward the central section.

5. In a machine for making metal castings, the combination of a stationary support, a central mold section rigidly secured to the support, two movable mold sections at opposite sides of the central section and adapted to coöperate therewith to form two complete molds, the said movable sections having apertures extending in the direction of movement, unitary guide pins extending through the fixed mold section and projecting at their ends into and closely fitting the walls of the apertures of the movable sections, means for simultaneously moving the side mold sections toward and away from the central section, and means for supplying molten metal to the molds when the movable sections are in operative positions.

6. In a machine for making metal castings, the combination of a stationary central mold section, two movable mold sections at opposite sides of the central section and adapted to coöperate therewith to form two complete molds, means for simultaneously moving the side mold sections toward and away from the central section, a reservoir for molten metal mounted in fixed relationship to the said central mold section, and valves for admitting metal from the reservoir to the two molds simultaneously when the movable sections are in operative positions.

7. In a machine for making metal castings, the combination of a stationary central mold section, two movable mold sections at opposite sides of the central section and adapted to coöperate therewith to form two complete molds, means for simultaneously moving the side mold sections toward and away from the central section, a reservoir for molten metal mounted in fixed relationship to the central mold section, valves for admitting metal from the reservoir to the two molds simultaneously, and

- automatically acting means for opening the said valves when the said side sections move into operative positions.
8. In a machine for making metal castings, the combination of a stationary central mold section, two movable mold sections at opposite sides of the central section and adapted to coöperate therewith to form two complete molds, means for simultaneously moving the side mold sections toward and away from the central section, a reservoir for molten metal mounted in fixed relationship to the central mold section, valves for admitting metal from the reservoir to the two molds simultaneously, and automatically acting means for successively moving the side mold sections into operative positions, opening the said valves, closing the said valves and moving the said side mold sections out of operative positions.
9. In a machine for making metal castings, the combination of a stationary central mold section, two movable mold sections at opposite sides of the central section and adapted to coöperate therewith to form two complete molds, means for simultaneously moving the side mold sections toward and away from the central section, a reservoir for molten metal mounted in fixed relationship to the central mold section, valves for admitting metal from the reservoir to the two molds simultaneously, and automatically acting means for successively moving the side mold sections into operative positions, opening the said valves, closing the said valves, moving the side mold sections out of operative positions and ejecting the castings from the said molds.
10. In a machine for making metal castings, the combination of a stationary support, a central mold section rigidly secured to the support, two movable mold sections at opposite sides of the central section and adapted to coöperate therewith to form complete molds, means for simultaneously moving the side mold sections toward and away from the central section, a reservoir for molten metal mounted entirely on the said fixed mold section, and valves for admitting metal from the reservoir to the molds when the movable sections are in operative positions.
11. In a machine for making metal castings, the combination of a stationary support, a central mold section rigidly secured to the support, two movable mold sections at opposite sides of the central section and adapted to coöperate therewith to form complete molds, means for simultaneously moving the side mold sections toward and away from the central section, a removable reservoir for molten metal designed to be held on the said fixed mold section by gravity alone, inter-engaging means on the mold section and the reservoir for preventing lateral movement of the reservoir, and valves for admitting metal from the reservoir to the molds when the movable sections are in operative positions.
12. In a machine for making metal castings, the combination of a stationary support, a central mold section rigidly secured to the support, two movable mold sections at opposite sides of the central section and adapted to coöperate therewith to form complete molds, means for simultaneously moving the side mold sections toward and away from the central section, a reservoir for molten metal designed to be detachably mounted above the mold sections, and valves and valve operating devices mounted entirely on the reservoir and detachable with it from the mold sections.
13. In a machine for making metal castings, the combination of a stationary support, a central mold section rigidly secured to the support, two movable mold sections at opposite sides of the central section and adapted to coöperate therewith to form complete molds, means for simultaneously moving the side mold sections toward and away from the central section, a removable reservoir for molten metal designed to be held on the said fixed mold section by gravity alone, and valves and valve operating devices mounted entirely on the reservoir and removable with it from the mold sections.
14. In a machine for making metal castings, the combination of two mold sections adapted when in contact to form a complete mold, means for moving one of the sections away from and toward the other, the said movable section being provided with a small recess adjacent and communicating with the casting space and with an aperture smaller than the recess extending into the said recess from the outside of the section along lines parallel to the lines of movement of the section, a pin slidably mounted in the recess having a head adapted to lie in and fill the recess, a collar on the pin outside of the mold section, a spring interposed between the mold section and the collar for normally holding the pin in its outermost position with the head in the recess, means for supplying molten metal to the mold when the sections are in contact, and an abutment positioned to be engaged by the collar on the pin as the mold section is moved whereby the said head is moved into the casting space to eject the casting therefrom.
15. In a machine for casting metal washers or other apertured metal articles, the combination of two mold sections adapted when in contact to form a complete mold, a pin slidably mounted in an aperture in one of the said sections and normally extending into the casting space for forming the aperture in the casting, an ejector pin slidably mounted in another aperture in the last said section and normally positioned with its in-

- ner end outside the casting space, means for supplying molten metal to the mold when the sections are in contact, means for moving one of the mold sections relatively to the other, and means dependent on the movement of the mold section for moving the first said pin to withdraw it from the casting space and for moving the second said pin to force it into the casting space thereby 10 ejecting the casting.
16. In a machine for casting metal washers or other apertured metal articles, the combination of two mold sections adapted when in contact to form a complete mold, 15 a pin slidably mounted in an aperture on one of the said sections and normally extending into the casting space for forming the aperture in the casting, means for limiting the sliding movement of the pin, in 20 both directions with respect to its mold section, means connected with the pin whereby the pin can be moved with respect to the mold section and the mold section then moved bodily with the pin toward or away 25 from the other section, and means for supplying molten metal to the mold when the sections are in contact.
17. In a machine for making metal castings, the combination of two mold sections 30 adapted when in contact to form a complete mold, means for supplying molten metal to the mold when the sections are in contact, a cylinder, a slidable piston in the cylinder connected to one of the mold sections to 35 move it with respect to the other, means for supplying motive fluid under pressure, two valves one for connecting the fluid supply means to one end of the cylinder and the other for connecting it to the other, and 40 means acting, first, to simultaneously move both valves to open one and close the other and thereby move the piston to bring the mold sections into contact, second, to admit a quantum of molten metal from the supply means to the mold, and third, to simultaneously move both valves to close the one and open the other and thereby move the piston to separate the mold sections.
18. In a machine for making metal castings, the combination of two mold sections 50 adapted when in contact to form a complete mold, means for supplying molten metal to the mold when the sections are in contact, a cylinder, a slidable piston in the cylinder connected to one of the mold sections to 55 move it with respect to the other, means for supplying motive fluid under pressure, two valves one for connecting the fluid supply means to one end of the cylinder and the other for connecting it to the other, two 60 gear wheels connected respectively to the valves, a slidable bar having two sets of rack teeth engaging respectively with the teeth of the gear wheels, and means acting, 65 first, to move the bar in one direction to turn the gear wheels and open one valve and close the other, whereby the piston is moved to bring the mold sections into contact, second, to admit a quantum of molten metal from the supply means to the mold, and, third, to move the bar in the other direction to turn the gear wheels and close one valve and open the other, whereby the piston is moved to bring the mold sections out of contact.
19. In a machine for making metal castings, the combination of two mold sections adapted when in contact to form a complete mold, means for supplying molten metal to the mold when the sections are in contact, a cylinder, a slidable piston in the cylinder connected to one of the mold sections to move it with respect to the other, means for supplying motive fluid under pressure, two valves one for connecting the fluid supply means to one end of the cylinder and the other for connecting it to the other, two gear wheels connected respectively to the valves, a slidable bar having two sets of rack teeth engaging respectively with the teeth of the gear wheels, two solenoids surrounding the bar for moving the bar in one direction when one is energized and in the other direction when the other is energized, thereby opening one valve and closing the other or closing the one and opening the other, and automatically acting means for admitting a quantum of molten metal from the supply means to the mold when the mold sections are brought into contact under the influence of one of the said solenoids.
20. In a machine for making metal castings, the combination of two mold sections adapted when in contact to form a complete mold, means for supplying molten metal to the mold when the sections are in contact, a cylinder, a slidable piston in the cylinder connected to one of the mold sections to move it with respect to the other, means for supplying motive fluid under pressure, two valves one for connecting the fluid supply means to one end of the cylinder and the other for connecting it to the other, two solenoids, means for opening one valve and closing the other when one solenoid is energized and for closing the one valve and opening the other when the other solenoid is energized, whereby the piston is moved to bring the movable mold section into or out of contact with the other section, and automatically acting means for admitting a quantum of molten metal from the supply means to the mold when the mold sections are brought into contact under the influence of one of the said solenoids.
21. In a machine for making metal castings, the combination of two mold sections adapted when in contact to form a complete mold, means for supplying molten metal to the mold when the sections are in contact, a cylinder, a slidable piston in the cylinder

connected to one of the mold sections to move it with respect to the other, means for supplying motive fluid under pressure, two valves one for connecting the fluid supply means to one end of the cylinder and the other for connecting it to the other, electrically controlled means for opening one valve and closing the other and for closing the one and opening the other, whereby the piston is moved to bring the movable mold section into or out of contact with the other section, and automatically acting means for admitting a quantum of molten metal from the supply means to the mold when the mold sections are brought into contact under the influence of the said electrically controlled means.

22. In a machine for making metal castings, the combination of two mold sections adapted when in contact to form a complete mold, means for supplying molten metal to the mold when the sections are in contact, a motor for moving one of the sections away from or toward the other, means for supplying power to the motor, and an electrically controlled device supplemental to the motor and supplemental to the means for supplying power thereto for controlling the operation thereof.

23. In a machine for making metal castings, the combination of two mold sections adapted when in contact to form a complete mold, electrically controlled means for moving one of the sections away from or toward the other, a reservoir for molten metal above the mold sections, a valve for admitting metal from the reservoir to the mold sections, electrically controlled means for opening the valve, and a common automatically acting controller for the said mold section moving means and the said valve moving means.

24. In a machine for making metal castings, the combination of two mold sections adapted when in contact to form a complete mold, electrically controlled means for moving one of the sections away from or toward the other, a reservoir for molten metal above the mold sections, a valve for admitting metal from the reservoir to the mold sections, electrically controlled means for opening the valve, a common automatically acting controller for the said mold section moving means and the said valve moving means, the said controller acting to open the valve, to close the valve, to separate the mold sections and to bring the mold sections together.

25. In a machine for making metal castings, the combination of two mold sections adapted when in contact to form a complete mold, electrically controlled means for moving one of the sections away from and toward the other, a reservoir for molten metal, a valve for admitting molten metal from the reservoir to the mold when the sections are in contact, electrically controlled means for operating the valve, a rotatable controlling mechanism provided with means for making and breaking connections successively to cause the movable section to move into contact with the other section, to cause the valve to open, to release the valve to permit it to close, and to cause the movable section to move away from the other section, and a motor for driving the controlling mechanism continuously.

In testimony whereof I affix my signature, in presence of two witnesses.

PAUL S. MENOUGH.
